UNITED STATES PATENT OFFICE.

CHARLES MYTTON BROOKE AND HENRY KAIAPOI BROOKE, OF MELBOURNE, VICTORIA, AUSTRALIA.

DESIGN FOR A BOTTLE.

No. 38,755.

Specification for Design.

Patented Aug. 20, 1907.

Application filed July 13, 1907. Serial No. 383,707. Term of patent 14 years.

To all whom it may concern:

Be it known that we, CHARLES MYTTON BROOKE and HENRY KAIAPOI BROOKE, both subjects of the King of Great Britain, and residents at the corner of King street and Wharf Road, Melbourne, in the State of Victoria and Commonwealth of Australia, trading as C. M. BROOKE & SONS, lemon squash and peel manufacturers, have invented a new, original, and ornamental Design for a Bottle, of which the following is a specification, reference being had to the accompanying drawings, forming a part thereof, in which—

Figures 1 and 2 are respectively a rear and a front perspective view of a bottle, showing our new design; and Fig. 3 is a bottom or inverted plan view of the same.

We claim:—

The ornamental design for a bottle, as shown.

CHARLES MYTTON BROOKE.
HENRY KAIAPOI BROOKE.
